SHOE

Adolph F. Filsinger, Wausau, Wis.

Application October 2, 1936, Serial No. 103,659

1 Claim. (Cl. 12—142)

This invention appertains to welt shoes, and to a novel method and process of constructing the same.

In welt shoes, a relatively heavy insole is used, and this insole is slit or channeled to form a raised lip so that the upper and welt can be sewed thereto. The insoles are exceedingly expensive and the operation of channeling and forming the lip adds to the cost of manufacture. In some instances, it is necessary to reinforce the lip by canvas to prevent the tearing of the lip during the inseaming operation, and this adds further to the cost of the shoe. Other disadvantages are also had with the use of ordinary insoles, such as the reduction of the flexibility of the shoe and liability of not forming the lip on the true outline or shape desired.

It is, therefore, one of the primary objects of my invention to provide a welt shoe having an insole, which will also form the sock lining, formed from exceedingly light material, such as upper leather, with the edge thereof turned outwardly to form a flange or lip to which the upper and welt is sewed, so that an exceedingly inexpensive and flexible shoe will be had.

Another salient object of my invention is the provision of means whereby a shoe can be made with any material as an insole, regardless of weight, which is strong enough to hold an inseamming stitch.

A further object of my invention is the provision of a novel attachment for the last, whereby the light insole can be effectively handled to permit the inseaming operation without the tearing of the material, and to permit the forming of a well-shaped shoe.

A further important object of my invention is the provision of a removable insert or pattern for effectively holding the insole material on the last without stretching and for defining the fold for the flange or lip to which the welt and upper are sewed, so as to create a positive or desired shape.

With these and other objects in view, the invention consists in the novel construction, arrangement, and formation of parts, as will be hereinafter more specifically described, claimed, and illustrated in the accompanying drawings, in which drawings:

Figure 1 is a top plan view of a last constructed in accordance with my invention.

Figure 2 is a transverse sectional view through the last, taken substantially on the line 2—2 of Figure 1, looking in the direction of the arrows.

Figure 3 is a side elevational view of a last with the insole held thereon by the removable insert or hold-down, parts of the figure being shown broken away and in section.

Figure 4 is a fragmentary longitudinal sectional view through the last, with the upper lasted in place and sewed together with the welt to the flange formed on the margin of the insole.

Figure 5 is an enlarged, fragmentary detail view, showing the shoe after the trimming operation.

Figure 6 is a longitudinal sectional view through a last and shoe, showing a modified process of carrying out my invention.

Figure 7 is a fragmentary transverse sectional view through a completed shoe made in accordance with my process.

Referring to the drawings in detail, wherein similar reference characters designate corresponding parts throughout the several views, the letter L generally indicates a last utilized in constructing my shoe. This last can be of substantially the ordinary character, with the exception that I form a marginal rib 10 thereon, which has a thickness equal to the thickness of the material which is to be used as the combination insole and sock lining.

The rib 10 can be formed on the last or secured thereto in any desired manner, and for the purpose of illustration I have shown the rib held on the last by means of tacks 11. The rib 10 forms a permanent part of the last, and the purpose thereof will more fully appear as the description proceeds.

As heretofore brought out, with my method I can utilize any material as an insole which is strong enough to hold an inseam stitch, regardless of weight. Thus, if desired, I can use upper leather as the insole.

The first step in my process of forming the new welt shoe consists in placing the insole 12 formed from the light material on the face of the last against the inner edge of the marginal rib 10. I then utilize a relatively stiff insert, pattern, or hold-down 13, which also has a thickness substantially equal to the thickness of the rib 10 and the thickness of the material used for the insole.

The outer edge of the insert 13 follows the shape of the contour of the last and the rib 10, but it is formed smaller than the last and rib, so that the material from which the insole is formed can extend between the rib 10 and the insert. After the insert 13 has been properly disposed on the last, removable tacks 14 are employed for tem-

porarily holding the insert 13 and the insole 12 in place.

The rib 10 and the insert 13 form an accurate means to permit the folding back of the margin of the insole to provide the attaching flange or lip 15. As the lip or flange 15 has to follow the contour of the insert 13, a positive shape or outline will be given the lip or flange, which will bring about the making of the desired and prop-
10 erly shaped shoe.

After the insole and insert have been secured in place and the flange has been turned outwardly, as shown in Figure 3, the upper 16 can be lasted over the last L and rib 10, after which
15 the upper edge and the welt 17 are secured by inseam stitching 18 to the lip or flange 15.

When the inseaming operation has taken place, then the edges of the flange or lip 15, the upper, and the welt can be trimmed down close
20 to the inseaming stitching 18, as at 19 (referring to Figure 5 of the drawings).

After the inseaming and trimming operations have been performed, the shoe can be handled and the other operations performed in the ordinary way.
25

Some manufacturers may object to utilizing a special form of last to fabricate the shoe, and in such instances, the rib 10 can be eliminated. Where the rib 10 is eliminated, the shoe is constructed in a slightly different manner, and I then utilize inner and outer removable sections 20 and 21. The section 20 takes the exact outline of the last and provides means to build up the last to compensate for the thinness of the material used in the insole.
35

When the inner section 20 has been placed on the last, then the insole 22 is placed on the upper face of the section 20, and the top section 21 is accurately placed on the outer face of the insole.
40 These three parts are then secured to the last in any preferred manner, such as by tacks 23.

The outer section 21 forms a pattern and terminates inwardly of the inner section 20 and provides a guide whereby a flange or lip 24 can be easily turned outwardly on the insole. The pattern in this method also accurately defines the shape or outline of the flange or lip 24. After the lip 24 has been folded outwardly, then the upper 25 is lasted in place and the edge of the upper, with the welt 26, is secured by the inseam stitching 27 to the flange or lip 24.
45

When the inseaming operation has been completed, then the edges of the insole, upper, and welt can be trimmed down close to the inseam stitches. After these operations have been completed, the outer section 21 is removed from the shoe, and the shoe is completed in accordance with accepted shoe manufacturing steps. When the shoe is removed from the last, the inner section 20 can be removed from the shoe.
55

It can be seen that in both processes the outer section or pattern 13, and the outer section 21

and the inner section 20 can be utilized over and over again.

In Figure 7 I have shown an outsole or wear sole 28 secured to the welt by means of stitching 29.
5

By my process I am enabled to utilize a cheap material for the insole, and this material, owing to its extreme thinness, creates a shoe of maximum flexibility, and the shoe is given a positive and desired shape.
10

In the drawings, I have eliminated the showing of the shoe lining, counter, toe boxes, and the like, in order to simplify the understanding of the invention, but it is to be understood that these parts can be utilized when necessary or 15 preferred.

My process entirely eliminates the sock lining and heel padding of shoes, as the inseaming which is ordinarily sewed to form a portion of the insole, in my shoe is sewed to that portion which, 20 after the last is removed from the shoe, creates the sock lining of the shoe and acts both as a sock lining and an insole in the shoe.

My construction facilitates the use of an exceedingly light material, which heretofore was 25 impossible to use, because in bed lasting the toe and heel seat, an extremely light material could not be handled, due to the fact that in the construction of the shoe, the machines working on the shoe would ruin it in the making.
30

In my process I so reinforce this light insole material with my insert or hold-down that as the shoe is being inseamed, it so anchors the material that it creates a shape which is as positive as the exact outlines of the last. This is 35 due to the raised marginal part of the last and the insert which holds the material and creates a more nearly perfect outline than a heavy channeled insole.

In use of my construction on heeled shoes or 40 shoes which must carry shanks, a fibre may be used from the back of the insole to the ball of the last, the same as in other types of shoes. When my construction is used on spring heeled shoes without shanks, it is ideal.
45

Changes in details may be made without departing from the spirit or the scope of my invention, but what I claim as new is:

The process of constructing a shoe which consists in utilizing an insole of extremely thin material, placing said insole on a last having a marginal raised edge, placing an insert of predetermined form and less width and length than said last and of a smaller size than the inner edge of the marginal raised portion of the last on the 55 insole, and securing the insert and insole on the last against movement, turning up the marginal edge of the insole between the insert and the marginal raised portion of the last, and securing an upper and a welt to the upturned portion of the insole.
